Dec. 1905

John G. Tolson, of Winchendon, Mass.
Letters Patent No. 9905-Dated March 1st 1864.
Design for a Spool Holder for Sewing Machines.

The schedule referred to in these Letters Patent and making part of the same.

To all whom it may concern:

Be it known that I, John G. Tolson, of Winchendon, in the County of Worcester and State of Massachusetts, have invented a new Design for a Spool Holder for Sewing Machines; and I do hereby declare that the following is a full, clear and exact description of the same, reference being had to the accompanying drawings, forming part of this specification, in which:

Figure 1. is a side view of the spool holder.

Figure 2. is a front view of the same.

Similar letters of reference indicate corresponding parts in all cases where they are used in the two figures.

The spool holder is composed of a base B, and perpendicular standard C joined by a curve as shown at any figure 1. The upper surface of the base and back or inner surface of the standard are flat or nearly so, terminating at the edges in a fillet, b, see figure 1. The sides of the base and standard and the front of the standard are ornamented, in relief, with a combination of flower and scroll work.

The upper part of the standard is circular or nearly so and has upon it a flower-like ornament c. d. which is shown in both figures and below this there are upon the sides of the standard leaves e, which unite with ornaments f. g. consisting of a combination of leaf and scroll on each side of the curve a, which unites the standard and base. On each side of the base there is a central leaf ornament g. (Figure 1) which merges into two similar ornaments h. h. which are a combination of leaf and scroll, the ornament h. meeting one of the ornaments f. g. and that h. extending to the other end of the base.

2.

Des 1905

The piece D. in the drawing is no part of the design but is the upper part of the needle bar to which the spool holder is secured.

What I claim as my invention, and desire to secure by Letters Patent is

The design and configuration of the spool holder herein described and represented in the accompanying drawings.
